UNITED STATES PATENT OFFICE.

GEORGE M. KNEUPER, OF NEW YORK, N. Y.

FILTER.

962,031.

Specification of Letters Patent. Patented June 21, 1910.

Application filed November 28, 1908. Serial No. 464,872.

To all whom it may concern:

Be it known that I, GEORGE M. KNEUPER, United States citizen, resident of the borough of Brooklyn, county of Kings, city 5 and State of New York, have invented certain new and useful Improvements in Filters, of which the following is a specification.

My invention relates to filters and has for 10 its object to improve the construction and efficiency thereof and particularly to provide a means for permitting any water which may remain in the filter after the cock has been closed to drain off.

15 My invention will be fully described hereinafter and the features of novelty will be pointed out in the appended claims.

Reference is to be had to the accompanying drawings in which—

20 Figure 1 is an elevation of my improved filter and Fig. 2 is a sectional view thereof on line 2—2 of Fig. 1.

In the drawings A is a pipe connected with a valve casing B, which in turn is connected by means of an inlet pipe C with a 25 source of liquid supply. D is a nozzle which also communicates with the said valve casing B in which is operatively located the valve or cock E. A passage E' is formed 30 in the said valve or cock, which valve is operated through the medium of the handle E², the usual stops being provided for limiting the movement in either direction.

F is a receptacle which forms part of or 35 is secured to the pipe A at a distance above the valve casing B and F' is the outlet for the filtered liquid.

G is a support formed of spaced bars having 40 their ends secured in rings G', and G² is the filtering material which is wrapped around said support and secured thereon by the perforated cylinder G³. The filtering material G² is somewhat wider than either the support G or the cylinder G³ and the ends 45 thereof are turned inward as clearly shown in Fig. 2. A plate H is arranged to slip over the pipe A and engages the upper in-turned portion of the filtering material and is secured in position by a nut H' which 50 screws on the pipe A at A', a washer H² being interposed between the nut and the plate H. As the nut is screwed down on the pipe the filtering material with the support G and cylinder G³ is clamped in position 55 about the pipe A between the bottom of the receptacle F and the plate H. A cover I

of glass or similar material has its one end in engagement with a ring washer I' located at the upper edge of the receptacle F and is provided at its other end with a central aperture through which the pipe A extends. The upper end of the pipe A is screw-threaded to receive the air chamber J, the lower part of which abuts against a washer J' adjacent to the upper end of the 60 cover I and serves to secure the said cover in position.

J² is an air inlet valve located in a chambered plug J³ which screws into the upper portion of the air chamber J. 70

The pipe A is provided at a point within the support G with an aperture A² and is further provided with openings A³ and A⁴. The openings A³ are so positioned on the pipe A as to be flush with the bottom of the 75 receptacle F, while the openings A⁴ are located in a slightly higher plane.

K is a metal or other cylinder which loosely surrounds the pipe A at the point where the openings A³ and A⁴ are located 80 and rests on the bottom of said receptacle F.

L is a passage formed in the valve casing B the purpose of which will be more clearly brought out hereinafter.

In operation when a supply of filtered 85 liquid is desired the handle E² is turned down until the passage E' establishes communication between the inlet pipe C and the pipe A. The liquid now flows through said passage E' and pipe A and out through 90 the openings A³ and A⁴ and is diffused by the cylinder K so as not to continually strike the filtering material in the same spot. From the interior of the support G the liquid passes through the filtering material and through the perforated cylinder 95 G³ and out through the outlet F'. As soon as the cock is opened as just described the air contained in the interior of the filter is compressed by the rising liquid and closes 100 the air valve J² and is then forced through the filtering material by the continued pressure of the liquid entering through the pipe A. This results in a perfect aeration of the filtering mass. After enough filtered liquid 105 has been secured, the handle E² is moved back to its initial position which brings the valve or cock E to the position shown in Fig. 2. In this position the passage E' connects the pipe A with the passages L so that any 110 liquid which remains in the interior of the support G will flow under the cylinder K

and back through the openings A³ into the pipe A. From the pipe A the said liquid will pass through the passage E' and will flow out through the passage L. During 5 this operation air will enter through the air chamber into the pipe A and through the opening A² to the space between the support G and the pipe A. The filter is thus completely emptied each time and it is impossible 10 for any liquid to remain in the filter and become stagnant. When unfiltered liquid is desired the handle E² is moved down until the passage E' establishes communication between the pipe C and the nozzle D.

15 Various modifications may be made without departing from the nature of my invention as defined in the claims.

I claim as my invention:

1. In a filter, a casing provided with an 20 outlet, an inlet pipe extending through said casing and communicating at the top with an air chamber and provided near the bottom of said casing with apertures, a ring surrounding said inlet pipe at the apertures

and spaced therefrom for diffusing the entering liquid, and a filtering material surrounding said stand pipe. 25

2. In a filter, a casing provided with an outlet, an inlet pipe extending through said casing, an air chamber at the top of said casing in communication with said inlet pipe, said inlet pipe being provided near the bottom of the casing with apertures, a ring surrounding said pipe at the apertures and spaced therefrom for diffusing the entering 30 liquid, a support surrounding said pipe, a filtering material arranged on said support and means on said pipe for maintaining said filtering material and supporting operative 35 position. 40

In witness whereof I have hereunto set my hand in the presence of two subscribing witnesses.

GEORGE M. KNEUPER.

Witnesses:

JOHN A. KEHLENBECK,
JOHN LOTKA.
